CLAIM

The ornamental design for a display screen with graphical user interface, as shown and described.

DESCRIPTION

FIG. 1 shows a front view of an embodiment of a display screen with graphical user interface; and, FIG. 2 shows a front view thereof, showing the design of FIG. 1 in a differing broken-line context.

The outermost broken-line border shows the perimeter of the display screen and forms no part of the claimed design. The remaining broken lines illustrate portions of the graphical user interface and form no part of the claimed design.
